By ATTORNEY

UNITED STATES PATENT OFFICE.

ELBERT E. HAWKINS, OF UNADILLA, NEW YORK.

TENSION-LUG FOR SILOS, &c.

1,315,119.

Specification of Letters Patent.

Patented Sept. 2, 1919.

Application filed September 5, 1917. Serial No. 189,739.

To all whom it may concern:

Be it known that I, ELBERT E. HAWKINS, citizen of the United States, and resident of Unadilla, county of Otsego, and State of New York, have invented an Improvement 5 in Tension-Lugs for Silos, &c., of which the following is a specification.

The object of my invention is to provide a yielding tension lug for hoops employed 10 upon silo bodies and for other uses such as large tanks, etc., where there is considerable expansion and contraction due to the varying temperature conditions.

My object is further to provide in such 15 tension lugs a simple and inexpensive construction, which is easily manufactured at a low cost and sufficiently yielding that it will adapt itself to conditions to be met with in practice. Not only is the lug made yielding 20 in the direction of its length, but it is also free to flex laterally to suit the curvature of the silo, tank, etc., and thereby lie close to the outside surface thereof and receive the 25 tangentially extending ends of the hoop or band.

My invention consists of a coil spring of 30 steel rod, having its ends extended to a very considerable length and bent at their extremities to form loops or eyes through which the hoop ends pass and against which

35 the nuts of the hoop ends press. My invention also includes the employment of a loose link threaded lengthwise through the coil to limit its extension beyond the critical limit of elasticity and thus prevent the "setting" of the spring by putting too much tension thereon when tightening the hoops.

40 My invention also comprehends details of construction which, together with the features above stated, will be better understood by reference to the drawings, in which:

Figure 1 is a front view of my improved tension lug applied to the hoop ends; Fig. 2 45 is a side view of the same; Fig. 3 is a plan view of the same; and Fig. 4 is a perspective view of the tension lug removed from the hoop.

A is a coil constituting a spring, in which 50 all of the coils normally rest close together, as in Fig. 4. The ends of this coil are extended in relatively long arms B, B, in substantial alinement; and the ends of these arms are bent into loops C, C, to constitute 55 eyes which receive the hoop ends E, E. The

arms B, B, are not only in alinement with each other but are also preferably arranged in substantial alinement with the side of the coil A, so that when the lug is stretched and resting against the surface G of the silo or 60 tank, both the coil and arms rest against the wooden surface of the same and hence the lug, as a whole, assumes a curved shape commensurate with the curvature of the silo or tank, be it of large or small diameter. 65 Similarly, it will be noted that the looped ends C, C, lie in planes radial to the curvature and axis or vertical center of the silo or tank and hence at right angles to the tangential ends E, E, of the hoop, as will be more 70 readily understood by reference to Fig. 3. This adaptability of the parts will enable the nuts F, F, of the screw threaded hoop ends to rest properly upon the looped ends C, C, and permit them to be freely rotated in 75 putting the hoop under tension.

By having the arms B, B, in alinement the pull is direct at each side and there is no tendency to twist the coil out of position, no matter how much tension is put upon it. It 80 will also be seen that when the arms may not be sufficiently long to permit the taking up of the hoop ends, said ends may extend into the coil A, as there is no obstruction. Furthermore, this alinement of the parts permits easy assembling upon the hoop ends, as the lug may be slid back upon one hoop end and after being alined, shifted in the opposite direction upon the other hoop end. In 85 this case the nut may already be applied to the hoop end upon which the lug was first adjusted, and after its adjustment to the other hoop end, the nut of that end may be applied.

The tension lug is made of steel, but to 90 prevent too much stretching with danger of "setting", the coils and thereby losing the elasticity, I provide a limit link D which extends through the coil A and has its ends d, d, bent over downwardly to form hooks 100 which will limit the spreading of the outermost or end coils and thus limit the tension which may be put upon the device. Even when so limited, it will be observed that as the link D is at the bottom (assuming that 105 position by gravity) and as the arms E, E, are near the top of the coil A, the latter will still have some capacity for a little extra stretching, so that it is yielding in both directions when the link is in full play as a 110

stop. The capacity for contraction is always present, so that the lug will meet all commercial requirements in use.

I have shown my improved tension lug in the form which I have found best adapted for actual use and while I prefer the same, I do not restrict myself to the minor details, as it is manifest that these may be modified without departing from the spirit of the invention.

Having now described my invention, what I claim as new and desire to procure by Letters Patent, is:

- 15 1. In a device of the character stated, a coil spring having two oppositely extending laterally yielding arms in approximate alinement with each other and with one side only of the coil spring, the ends of said arms bent into loops whose planes are at substantial right angles to the length of the arms and in which the alinement of the apertures of said loops is normally in alinement with the loops of the coil spring portions, said arms and spring adapted to be bent into a curve when applied to a tank-like body and when so applied the apertures in the looped ends of the arms assuming a tangential alinement to the general curvature of the device.
- 20 2. In a device of the character stated, a coil spring having its ends continued in two oppositely extending horizontal and laterally yielding arms in approximate alinement with each other and with one side only of the coil spring, the ends of said arms bent into loops whose planes are at substantial right angles to the length of the arms and in which the alinement of the apertures of said loops is normally in alinement with the loops of the coil spring portions, said arms and spring adapted to be bent into a curve when applied to a tank-like body and when so applied the apertures in the looped ends of the arms assuming a tangential alinement to the general curvature of the device.
- 25 3. In a device of the character stated, a coil spring having two oppositely extending laterally yielding arms in approximate alinement with each other and with one side only of the coil spring, the ends of said arms bent into loops whose planes are at substantial right angles to the length of the arms and in which the alinement of the apertures of said loops is normally in alinement with the loops of the coil spring portions, said arms and spring adapted to be bent into a curve when applied to a tank-like body and when so applied the apertures in the looped ends of the arms assuming a tangential alinement to the general curvature of the device.
- 30 4. In a device of the character stated, a coil spring having its ends continued in two oppositely extending horizontal and laterally yielding arms in approximate alinement with each other and with one side only of the coil spring, the ends of said arms bent into loops whose planes are at substantial right angles to the length of the arms and in which the alinement of the apertures of said loops is normally in alinement with the loops of the coil spring portions, said arms and spring adapted to be bent into a curve when applied to a tank-like body and when so applied the apertures in the looped ends of the arms assuming a tangential alinement to the general curvature of the device.

Copies of this patent may be obtained for five cents each, by addressing the "Commissioner of Patents
Washington, D. C."

ment with each other and with one side only of the coil spring and the ends of the said arms provided with loops, combined with a loose link threaded through the coil spring and bent over at its ends to form hooks for restricting the stretching of the coils of the spring, said link being of greater length than the unstretched length of the coil spring portions and arranged at the lower part thereof out of alinement with the arms.

35 3. In a device of the character stated, a tension lug formed of a coil spring having oppositely directed arms arranged in substantial alinement with the one side only of the coils of the spring and having their ends provided with looped portions transversely arranged and on the same side of the arm as the coil spring projects, said spring and arms when under tension assuming a curvature along their length, and a hoop having its ends tangential to the curvature of the tension lug device and extending through the looped ends of the arms so as to point outwardly and away from the spring coil, and nuts screwed upon the ends of the hoop and pressing upon the looped ends of the arms to stretch and curve the tension lug as a whole.

40 In testimony of which invention, I hereunto set my hand.

45 ELBERT E. HAWKINS.
